UNITED STATES PATENT OFFICE.

FRANK B. COOK, OF CHICAGO, ILLINOIS.

HEAT-COIL.

No. 854,272.

Specification of Letters Patent.

Patented May 21, 1907.

Application filed November 7, 1903. Serial No. 180,200.

To all whom it may concern:

Be it known that I, FRANK B. COOK, a citizen of the United States, residing at Chicago, in the county of Cook and State of Illinois, have invented new and useful Improvements in Heat-Coils, of which the following is a full, clear, concise, and exact description, reference being had to the accompanying drawings, forming a part of this specification.

My invention relates to a heat coil, my object being to provide an automatic, self-restoring coil, adapted to be used as a protective device for electrical circuits.

Heat coils generally in use, are of such a nature that after they have been operated by an abnormally strong current, their members are in such a condition and position, relatively to each other, that the said coils are not in condition for immediate use, and therefore have to be replaced by other coils. I have in mind, heat coils in which certain portions thereof are disintegrated by the heat produced in the coil, by abnormally strong currents therein, the said portions not returning to their normal, relative positions when the coil has cooled. Such coils are inconvenient and expensive as they necessarily have to be replaced by other coils, after they have operated.

In my present invention, I have shown a heat coil in which all of the parts have the same relation to each other, after the coil has been operated and cooled, as they normally had before the operation of the coil. For this reason, the same coil may be used over, again and again, it being in the same condition as originally. This is a great saving in maintenance, and is also very convenient, especially where a large number of circuits are to be protected.

This present invention may be adapted and applied to various forms of circuits and under various conditions, but it is particularly adapted to telephone lines and systems where protection of delicate instruments is a very essential necessity. In large telephone systems, where a great many circuits are to be protected, the space occupied by protective apparatus is of great importance, and I have therefore endeavored to make this heat coil a compact and efficient arrangement to be used in this connection.

The principles involved in this invention are not necessarily confined to telephone work. They may be adapted to any form

of electrical circuits wherein protection from abnormally strong currents is desired.

In this present invention I employ a heat-conducting member, upon which the coil proper is wound, and end pieces, which, with the heat-conducting member, form a spool for containing the said coil. One end of the spool is permanently secured to the core of the spool while the other end is secured to the said core by a fusible material. This core is the above mentioned heat-conducting member, and through it the heat from the coil is conducted to the fusible material. When the fusible material is softened, it allows the relative position of the core and end of the spool containing the fusible material, to change, and thereby, cause the said coil to operate, immediately after which the said core and spool end are restored to their normal, relative position, with respect to each other, by a suitable arrangement adapted for the purpose, before the fusible material has had time to cool. When the fusible material does cool and harden, it again solders the said core and spool end together, as at first, and the coil is again ready for use, as before its operation. In the operation of the coil, it may open a circuit, close a circuit, or do both, as is required; but under all conditions the arrangement must be such that the parts of the coil are restored to their normal, relative position, immediately after operation.

The invention herein, lies particularly in the combination of the heat-conducting core, fusible material, spool end, coil for producing heat, and means for restoring these parts to their relative, normal position, after operation, as shown in the accompanying drawings, and as will be hereinafter described.

Another feature of this invention is the method by which the core of the spool is permanently secured to, and insulated from, one end of the said spool.

I will more particularly describe my invention by reference to the accompanying drawings, in which—

Figure 1 is a side view of the heat coil, somewhat enlarged; Fig. 2 is an end view of the said coil, taken from Fig. 1; Fig. 3 is a sectional view of the heat coil, taken on line E F of Fig. 2; Fig. 4 and Fig. 6 are views showing the heat coil in service, in combination with its means of operation and restoration; Fig. 5 and Fig. 8 show a modified form of Figs. 4 and 6, the modification being in the

springs of the arrangement; and Fig. 7 is a view showing the heat coil in service, in an operated position.

Like characters refer to like parts in the several figures.

The heat coil as a whole, is best seen in Fig. 1 where it is shown in its entirety. In Fig. 3 it will be seen that the coil proper *k*, is wound upon a metal core *e*. The coil *k* furnishes means for producing heat, and the core *e* acts as a conductor of this heat, conveying it to where it is to be utilized. The core *e* is provided with two annular projections thereon, one at *o* and one at *h*. The part *o* is held between two insulating disks, or washers, *n* and *m*. The metal disk *f* is supplied with a hollow cylindrical projection *l* which is a part of *f*. In this hollow cylinder *l*, is held the insulating washers *n* and *m* and the projection *o*, as shown in Fig. 3, these parts *n*, *o* and *m* being held securely in place by the cup-shaped portion of *l* which is formed over, as shown in Fig. 3, thus insulating the core *e* from the disk *f*. As will be seen in Fig. 3, the core *e* extends through the washer *m*, and as *e* carries the annular projection *h*, the washer *m* may be split before it is put in place. It will also be noticed that the outside diameter of *o* is considerably smaller than the inside diameter of *l*. The conical-shaped projection *g* is attached to *f* and is preferably a part thereof. The end cap *B*, Fig. 1, is composed of two annular projections, or flanges, *b* and *d*, and the cylindrical portion *c* which is centrally bored as shown at *r*, Fig. 3. The cap *B* is made of metal. The annular projection *h* fits loosely in the bore *r*, against a shoulder at the inner end of *r*, and is held thereto by a solder which is shown at *i*. There is enough play between *h* and *r* so that when the solder *i* is melted or softened, the turning motion of *h*, in *r*, with one point of *i* as the fulcrum, is considerable. The ends *p* and *q* of coil *k* are soldered to parts *c* and *l*, respectively. The coil *k* is entirely inclosed by the hollow cylindrical casing *a*, of insulating material. The casing *a* fits loosely between *b* and *f*, on its end surfaces, in order not to interfere with the motion of *h*, in *r*, when the solder *i* is softened.

In assembling the device, the end cap *B* is first threaded upon the core *e* by passing the annular projection *o* through the hole in the inner end of the cap *B*. Then washer *n*, annular projection *o* and split washer *m* are placed within the cap-shaped portion of end cap *f* which is then formed over as at *l* to firmly hold *n*, *o* and *m* thereon. The annular projection *h* is then soldered within the bore *r* by an easily fusible solder *i*, after which the winding *k* is wound upon the core *e* and the ends *q* and *p* of winding *k* soldered to end caps *f* and *B*, respectively, by a hard solder. Then the shell *a*, which is split longitudinally, is slipped in place over the cap *f* to completely inclose the winding *k*.

In Figs. 4 and 6, the heat coil is shown in service. The springs *t* and *u* are the springs to which the respective circuit wires 1 and 2, of the circuit to be protected, are connected. A portion of spring *t* is cut away, to show the method employed for holding the conical-shaped projection *g*, in spring *t*. Spring *u* is provided with a slot in its upper end for receiving one end of the heat coil. Spring *s* is a ground plate, conductor 3 connecting *s* with the ground. Springs *t*, *u* and *s* are mounted on a suitable support *v*. When the heat coil is put in place, the cap *B* is first inserted in the slot in spring *u*, the spring *u* passing between the flanges *b* and *d*. The conical-shaped projection *g* is then depressed and inserted through the conical-shaped hole *t*₁ in spring *t*. The diameter of the conical-shaped hole *t*₁ is somewhat larger than the diameter of *g*, so as to allow *g* to pass through the hole *t*₁ easily. Inserting *g* through the hole *t*₁, puts a bend in spring *u* and thereby causes the upper surface of *g* to engage the upper surface of the hole *t*₁, the two conical surfaces forming a catch for holding *g* to *t*₁. The heat coil is now in position for protecting the circuit of which springs *t* and *u* are a part. The currents traversing the circuit 1—2, also traverse spring *t*, projection *g*, disk *f*, cup *l*, winding *k*, cap *B* and spring *u*. When a strong current traverses this circuit, it heats the winding *k* of the heat coil, and this in turn heats the metal core *e*. The heat from *e* is conducted through the flange *h* to the fusible material *i*. When this heat is sufficient, it causes the fusible material *i* to soften, thus allowing the flange *h* to move in the bore *r* of cap *B*. This allows the projection *g* to drop down in the hole *t*₁, and the spring *u* to straighten somewhat, thus reducing the pressure between the surfaces of *g* and *t*₁. When this pressure is sufficiently reduced, the projection *g* slips out of the hole *t*₁, and the spring *u* takes the position shown by the dotted line *u*₂ of Fig. 6, or more clearly in Fig. 7. When the heat coil takes this new position it opens the circuit between 1 and 2, at *g*, and closes the circuit between 2 and 3, where the core *e* comes in contact with ground spring *s*. Thus it will be observed that if the instrument to be protected is included in circuit wire 1, and the strong current comes from circuit wire 2, the operation of the heat coil breaks the strong current of 2, from the instrument in 1, and connects this strong current to ground at 3, thus protecting the instrument in 1. In other words, the strong current from 2, is switched from 1 to 3.

As soon as the heat coil operates, and the core *e* strikes the ground plate *s*, the position of the flange *h*, relatively to the cap *B*, is brought back to the normal, by this contact; and as soon as the fusible material cools, the flange *h* is soldered to the cap *B*, as it was originally. The pressure between core *e* and

spring s , due to spring u , holds the flange h in place, while the solder i cools.

In Figs. 5 and 8, I have shown a modified form of the arrangement shown in Figs. 4 and 6. The modification is in the spring u_4 which is secured to spring u_1 . Spring u_1 in Figs. 5 and 8, corresponds to spring u in Figs. 4, 6, and 7. In Fig. 8, the spring u_4 rests against the end of core e . When the heat coil operates, as described above, the spring u_4 presses the flange h back to its normal position before connection is made between springs u_4 and s as shown in the dotted line view u_3 of Fig. 8. As spring u_4 is a light spring, it does not interfere with the operation of the heat coil when the projection g releases from hole t_1 of spring t ; it merely helps to restore h to its normal position and to make good contact between end cap B and spring u_1 .

While I have described particular details of construction in this invention, I do not wish to limit myself to such details. I therefore wish it to be understood that the invention herein, lies in the principles of action of the heat coil, more particularly than in the details of construction.

Having described my invention, what I claim as new, and desire to secure by Letters Patent, is—

1. In a heat coil, the combination of a heat-producing member, a heat-conducting member, a fusible material securing the heat-conducting member to another conducting member, and means apart from the heat coil, by which the members of the heat coil are restored to their normal, relative position, after the fusible material has been softened.

2. In a heat coil, the combination of a heat-producing member, a heat-conducting member, a fusible material, a centrally-bored, conducting member secured to the heat-conducting member by the fusible material, and means apart from the heat coil, whereby the members of the heat coil are restored to their normal, relative position, after the fusible material has been softened.

3. In a heat coil, the combination of a heat-producing member, a heat-conducting member, a centrally-bored, conducting member, through which the heat-conducting member passes, and a fusible material which secures the heat-conducting member to the centrally-bored, conducting member, as described.

4. In a heat coil, the combination of a heat-producing member, a heat-conducting member, a centrally-bored, conducting member, through which the heat-conducting member passes, a fusible material by which the heat-conducting member is normally secured to the centrally-bored, conducting member, and means whereby the members of the heat coil are restored to their normal,

relative position, after the fusible material has been softened.

5. In a heat coil, the combination of a heat-producing member, a heat-conducting member, a centrally-bored member through which the heat-conducting member passes, a fusible material by which the heat-conducting member is normally secured to the centrally-bored member, and means apart from the heat coil, whereby the members of the heat coil are restored to their normal, relative position, after the fusible material has been softened.

6. In a heat coil, the combination of a heat-producing element, a centrally-bored, conducting element, a heat-conducting element extending through the heat-producing element and the centrally-bored element, a fusible material which secures the heat-conducting element to the centrally-bored element, and means apart from the heat coil, by which the heat-conducting element and centrally-bored element are restored to their normal, relative position, after the fusible material has been softened, thus allowing their relative position to change, substantially as described.

7. In a heat coil, the combination of a heat-conducting element, a heat-producing element, a centrally-bored element, the heat-conducting element being inclosed by the heat-producing element and the centrally-bored element, and secured to the centrally-bored element by a fusible material, and means apart from the heat coil, whereby the relative positions of the elements of the heat coil are restored to the normal, after being allowed to change by the fusible material becoming softened, substantially as described.

8. In a heat coil, the combination of a heat-producing coil, a heat-conducting member, two centrally-bored, conducting members, the heat-conducting member being inclosed by the heat-producing coil and the two centrally-bored members, and being secured to one centrally-bored member and insulated therefrom, and secured to the other centrally-bored member by a fusible material, and means whereby the relative position of the members of the heat coil is restored to the normal, after being allowed to change by the softening of the fusible material, and secured by the fusible material hardening, substantially as described.

9. In a heat coil of the character described, the combination of a heat-producing coil, a heat-conducting core for the said coil, two centrally-bored, conducting members, forming ends of a spool of which the said heat-conducting core is the core, the said core carrying two annular projections which are inclosed in the respective centrally-bored members, one annular projection being secured to and insulated from one centrally-

bored member, by insulating washers, one on each side of the said annular projection, the other annular projection being conductively secured to the other centrally-bored member, by a fusible material, and means whereby, after the fusible material has been softened, thus allowing the relative position of the members of the heat coil to change, the normal, relative position of the members of the heat coil is restored, and secured by the fusible material becoming cool, substantially as described.

10. In a heat coil of the character described, a heat-producing element in the form of a coil, a spool for this coil, consisting essentially of two conducting end pieces and a conducting core normally secured thereto, the said end pieces being centrally-bored to receive respective annular projections of the 15 said core, one annular projection being secured to and insulated from one centrally-bored end piece, by insulating washers, one on each side of the annular projection, the other annular projection being secured to the other centrally-bored end piece by a fusible solder, a lug of conducting material secured to the outer surface of one end piece, a sleeve of insulating material inclosing the said spool from one end piece to the other, and 20 means for operating and restoring the heat coil, substantially as described.

11. In combination, as a protective device for electrical circuits, a heat-producing element inclosing a heat-conducting core, two 25 centrally-bored, conducting elements to which the said core is secured, the said core being insulated from one centrally-bored element, and conductively secured to the other by a fusible material, the centrally-bored elements being terminals for the heat-producing element, a lug secured to the outer face of one centrally-bored element and adapted to engage a spring, a second spring adapted to engage the other centrally-bored element, a 30 suitable base for the said springs, the said fusible material being heated and softened by an abnormally strong current traversing the heat-producing element, thereby allowing the normal, relative position of the elements of the heat coil to change, and the said lug to 35 release itself from the spring engaged therewith, and means cooperating with the said second spring when it operates, whereby the normal, relative positions of the said elements are restored before the fusible material has cooled, substantially as described.

12. In combination, as a protective device for electrical circuits, a heat-producing coil wound around a heat-conducting core, two 40 centrally-bored, conducting elements to which the said core is secured, the said core being insulated from one centrally-bored element, and conductively secured to the other by a fusible material, the centrally-bored elements being terminals for the heat-producing 45

coil, a lug secured to the outer face of one centrally-bored element and adapted to engage a spring, a spring provided with a hole therein, through which hole the said lug is normally inserted, a second spring provided with a slot therein and adapted to receive the other centrally-bored element, a third spring used as a ground connection, a suitable support to which the said springs are secured, the said fusible material being heated and softened by an abnormally strong current traversing the heat-producing coil; thereby allowing the normal, relative position of the elements of the heat coil to change, and thereby causing the said lug to release 50 itself from the hole in the spring engaged therewith, the action of the said second spring causing the said core to engage the said ground spring and thereby restore the elements of the heat coil to their normal, 55 relative position, where they are held by the fusible material becoming hardened, substantially as described.

13. In combination, as a protective device for electrical circuits, a heat-producing coil wound upon a heat-conducting core, two centrally-bored, conducting elements to which the said core is secured, one provided with an annular groove therein and the other provided with a conical-shaped lug secured thereto, the said core being insulated from one centrally-bored element, and conductively secured to the other by a fusible solder, the centrally-bored elements being terminals for the heat-producing coil, a 90 spring provided with a conical-shaped hole therein, with which the conical-shaped lug normally engages, a second spring provided with a slot therein and adapted to engage one of the centrally-bored elements at the 95 annular groove therein, a ground plate, a suitable support to which the said springs and ground plate are secured, the fusible material being heated and softened by the heat conducted thereto by the said core when an 100 abnormally large current traverses the said heat-producing coil, thereby allowing the said core to move in one centrally-bored element and thus cause the said lug to release 105 itself from the hole in the spring engaged therewith, the action of the second mentioned spring causing the said core to come in contact with the ground plate, thereby restoring the said core to its normal position in the said centrally-bored element to which it 110 was soldered, and changing the circuit from the said springs and heat coil, to the second mentioned spring and ground plate, substantially as described.

14. In combination, as a protective device 115 for electrical circuits, a heat-producing coil wound upon a heat-conducting core, two centrally-bored, conducting elements to which the said core is secured, one provided with an annular groove therein and the 120

other provided with a conical-shaped lug secured thereto and forming a part thereof, the said core being insulated from one centrally-bored element, and conductively secured to the other by a fusible solder, the centrally-bored elements being terminals for the heat-producing coil, two springs, one provided with a beveled hole therein and the other provided with a slot therein, the said springs being adapted to normally engage the respective centrally-bored elements, at the said groove and lug thereof, a third spring secured to the spring provided with a slot, and resting against one end of the said core, 15 a ground plate, a suitable support to which the said springs are secured, the fusible material being heated and softened by the heat conducted thereto by the said core, when an abnormally large current traverses the said 20 heat-producing coil; thereby allowing the said core to move upon its soldered support and thus cause the said lug to release itself from the spring engaged therewith, this action causing the last mentioned said spring 25 to engage the ground plate, thereby breaking the circuit between the first mentioned springs and closing a circuit between one of the first mentioned springs and the ground plate, the said third spring causing the said 30 core to be restored to its normal position upon its soldered support, and secured thereto by the cooling action of the fusible solder, substantially as described.

15. In an electrical circuit protector the 35 combination of an excess current operated device, circuit controlling mechanism co-operating therewith, and means apart from said device for placing the parts thereof in position for another operation.

40 16. In an electrical circuit protector the combination of a self-soldering heat cartridge, means for supporting the same, and means apart from said cartridge for placing the parts thereof in position for resoldering.

45 17. In an electrical circuit protector the combination with a heat cartridge, of means for supporting the same, and means apart from the cartridge for resetting the same to place it in condition to permit another operation.

18. In an electrical circuit protector, a heat cartridge provided with a central spindle having a solder connection with the cartridge in combination with means for placing said spindle into position for resoldering. 55

19. In an electrical circuit protector, a heat cartridge provided with a central spindle having a solder connection with the cartridge, means for heating and softening said solder connection on the passage of an unduly strong current, and means for placing said spindle in position for resoldering. 60

20. In an electrical circuit protector, a heat cartridge provided with a centrally disposed movable member having a solder connection with the cartridge, means for softening said solder on the passage of an unduly strong current to permit movement of said member, and means for placing said member in position in which the solder connection 65 can be hardened, whereby the central member will be resoldered.

21. In an electrical circuit protector, a heat cartridge provided with a centrally disposed movable member having a solder connection with the cartridge, means for softening said solder on the passage of an unduly strong current to permit movement of said member, and means apart from the heat 70 coil for placing said member in position in which the solder connection can be hardened, 75 whereby the central member will be resoldered.

22. In an electrical circuit protector, a heat cartridge comprising a centrally disposed movable member having a solder connection with the cartridge, a heat coil surrounding said central member, and means for placing said member in position to permit it to be resoldered after the solder has 80 been softened by heat generated in said heat coil. 85

In witness whereof I hereunto subscribe my name this 5th day of November, A. D. 1903.

FRANK B. COOK.
